CHANGEABLE CALENDAR

Michael J. Smith, % Arrow Art Finishers, Inc.,
1201 Evergreen Ave., Bronx, N.Y. 10468

Filed June 15, 1970, Ser. No. 23,484

Term of patent 14 years

Int. Cl. D19—03

U.S. Cl. D74—5

FIG. 1

FIG. 2

FIG. 5

FIG. 1 is a three-quartered perspective view of a changeable calendar showing my new design;

FIG. 2 is a top view of said changeable calendar;
 FIG. 3 is a front view of said changeable calendar;
 FIG. 4 is a back view of said changeable calendar;
 FIG. 5 is a left-hand view of said changeable calendar;
 FIG. 6 is a right-hand view of said changeable calendar; and

FIG. 7 is a bottom view of said changeable calendar.
 Different days and different months are displayed by shifting the positions of the cubes on the base and the squared prisms within the base.

I claim:

The ornamental design for a changeable calendar, substantially as shown and described.
